UNITED STATES PATENT OFFICE.

ALEXANDER McPHADEN, OF CHICAGO, ILLINOIS, ASSIGNOR, BY DIRECT AND MESNE ASSIGNMENTS, OF ONE-FOURTH TO JOSEPH T. SANDBERG, ONE-TENTH TO OTTO NELSON, ONE-TWENTIETH TO MARGARET ANDERSON, ONE-TWENTIETH TO ELSIE SWANSEN, AND ONE-TWENTIETH TO BEADA HEDLUND, ALL OF CHICAGO, ILLINOIS.

DESIGN FOR A GAME-BOARD.

52,827.

Specification for Design. Patented Dec. 31, 1918.

Application filed October 15, 1918. Serial No. 258,291. Term of patent 14 years.

To all whom it may concern:

Be it known that I, ALEXANDER McPHADEN, a subject of the King of England, residing at Chicago, in the county of Cook and State of Illinois, have invented a new, original, and ornamental Design for Game-Boards, of which the following is a specification, reference being had to the accompanying drawing, in which a plan view of the design is shown.

I claim:

The ornamental design for a game board, as shown.

In testimony whereof I affix my signature.

ALEXANDER McPHADEN.
